CHEMICAL COMPOUNDS

Willi Brun, Bridgeport, Conn., assignor to Remington Arms Company, Inc., a corporation of Delaware

No Drawing. Application August 26, 1937,
Serial No. 161,031

5 Claims. (Cl. 52—4)

This invention relates to certain new compositions of matter of an explosive character and the use of such compositions in detonators and ammunition priming compositions.

5 In patent application Serial No. 722,240 filed April 25, 1934, now Patent No. 2,116,878, May 10, 1938, by Brun and Burns there is disclosed the use, as an ingredient of ammunition priming mixtures, of a reaction product of lead nitrate and lead hypophosphate, this product probably being a double salt of lead nitrate and lead hypophosphate in molecular proportions. It is identified in said patent as lead nitrate hypophosphate, and is preferably prepared by first mixing lead nitrate 10 and lead hypophosphate in a dry condition and subsequently moistening the mixture. This compound contains in the same crystal both an oxidizer and a fuel which tend to react with each other under such a stimulus as a comparatively light blow. The use of compounds of this character in ammunition priming mixtures is very advantageous since the usual intergranular space separating fuel and oxidizer is wholly eliminated.

The present invention comprises the discovery 25 of certain other compositions which, like lead nitrate hypophosphate, probably are or contain complex compounds having within each crystal both a fuel and an oxidizer. They are likewise similar to lead nitrate hypophosphate in that 30 they are formed by the reaction of a nitrate and a hypophosphate, and preferably in the presence of a quantity of water inadequate to effect complete solution.

The most desirable nitrates are those of lead 35 and calcium. A nitrate of mercury may be used with non-alkaline hypophosphites. With calcium nitrate or lead nitrate there may be combined any soluble hypophosphate, such as a hypophosphate of ammonia, potassium, sodium, calcium, 40 strontium, barium, manganese, or lead. Each of the resulting compositions has certain characteristics which associate it with the nitrate from which it is derived. The group of nitrate hypophosphites derived from lead nitrate all exhibit 45 certain properties which are characteristic of lead nitrate-lead hypophosphate, while each of those derived from calcium nitrate exhibit properties which are characteristic of calcium nitrate-calcium hypophosphate. However, each individual member of each group possesses properties 50 which quite definitely identify it as a composition of matter distinct from all other members of either group. The reaction between the ingredients is probably incomplete especially under 55 the method of first preparing a dry mixture of

the reacting ingredients and subsequently moistening the dry mixture with a quantity of water inadequate to bring about complete solution.

The group characteristics are probably due to the formation of a double salt of the metal present in the nitrate; for example, lead nitrate hypophosphate has been quite definitely identified in the reaction product of lead nitrate and calcium hypophosphate, and in the reaction product of lead nitrate and strontium hypophosphate. 5 This reaction product possesses properties of explosiveness and stability quite similar to the properties of lead nitrate hypophosphate itself. It is non-hygrosopic, retaining its crystalline and explosive character after prolonged exposure to 10 conditions of high humidity and temperature. This fact is surprising since theoretically a reaction resulting in the formation of lead nitrate hypophosphate should leave a residue of hygroscopic calcium nitrate. In ammunition priming 20 mixtures the product performs the same function as lead nitrate hypophosphate produced in the usual manner. The calcium is apparently combined in some crystalline non-hygrosopic salt, which may be calcium nitrate hypophosphate. 25 The formation of this compound is theoretically possible according to the equation:

X-ray diffraction pictures show lines which are characteristic of lead nitrate hypophosphate. They do not show lines associated with calcium nitrate hypophosphate but this may be due to the extremely high absorption of X-rays by lead 35 compounds, and their comparatively slight absorption by calcium compounds.

The reaction product of calcium nitrate and lead hypophosphate possesses properties which differ substantially from the properties of the reaction product of lead nitrate and calcium hypophosphate; both being prepared by the technic of moistening dry mixtures of the reacting materials with a quantity of water insufficient to effect complete solution. In the reaction product of 45 calcium nitrate and lead hypophosphate thus treated, both lead nitrate and calcium nitrate-calcium hypophosphate have been identified. The product has something of the hygroscopic nature which is characteristic of calcium nitrate 50 and appears to be somewhat less desirable as an explosive than the reaction product of lead nitrate and calcium hypophosphate. The same is generally true of the reaction products of the nitrates of lead and calcium respectively with the 55

- soluble hypophosphites heretofore mentioned. The reaction product of each of the hypophosphites with lead nitrate appears to contain lead nitro hypophosphate, each may be exploded by 5 flame or impact, and each is substantially non-hygroscopic. The metal of the hypophosphate used, like the calcium in the reaction product of lead nitrate and calcium hypophosphate, is present in an unidentified but stable form.
- 10 The above-mentioned compositions of matter, particularly the reaction product of lead nitrate and calcium hypophosphate, have been found to serve the same purposes as lead nitro hypophosphate in ammunition priming mixtures and detonators, particularly detonators for such purposes as seismographic work.
- 15 A composition in accordance with the present invention may be prepared as follows: Dry calcium hypophosphate and dry lead nitrate of suitable granulation are thoroughly mixed in the proportions of 1.7 grams of calcium hypophosphate to 3.3 grams of lead nitrate. After thorough dry mixing, a quantity of water is added which is sufficient to completely wet the mixture without 20 completely dissolving its components. The moistened mixture is then thoroughly kneaded. After about two minutes of kneading the granular structure of the mixture begins to disappear. There is a loss in volume and a cement-like paste 25 is formed. The kneading is continued during the formation of this paste to prevent the setting of the composition into a rock-like mass and until the mixture is of uniform texture throughout. The occurrence of a reaction and the presence of 30 a reaction product are established by the change in texture and the loss in volume as well as by the behavior of the product when smeared on a plate. The moisture of the smear quickly evaporates leaving a finely crystalline residue.
- 35 40 After drying, the composition prepared in the manner above described may be used in ammunition priming mixtures and detonators in the same manner as lead nitro hypophosphate. Ammunition priming mixtures may also be prepared according to the method described in the above 45 mentioned patent, that is, by preparing a dry pre-mix of lead nitrate and calcium hypophosphate with the inert ingredients of a priming mixture, adding to the dry pre-mix an explosive ingredient 50 and the requisite amount of water and kneading the mixture until the completion of the reaction between the lead nitrate and the calcium hypophosphate; for example, the pre-mix may comprise 5 to 25 parts of calcium hypophosphate, 10 to 55 50 parts of lead nitrate, 6 to 12 parts of lead sulfocyanate, and 12 to 25 parts of glass. To this pre-mix is added 20 to 40 parts of such an explosive as

lead styphnate and the amount of water necessary to produce a mixture of the desired consistency. A specific example of such a mixture is as follows:

	Parts	5
Lead styphnate	33	
Calcium hypophosphate	7	
Lead nitrate	14	
Lead sulfocyanate	10	
Glass	20	10
Barium nitrate	16	

Mention has been made above of the double salt of calcium nitrate and calcium hypophosphate called, for convenience, "calcium nitro hypophosphate." This compound has been identified 15 by its X-ray diffraction picture in the reaction product of calcium nitrate and calcium hypophosphate, mixed dry and moistened with a quantity of water insufficient to effect complete solution.

Applicant having disclosed compositions of matter which are wholly new in themselves, as well as uses for such compositions, the appended claims are to be broadly construed.

What is claimed is:

1. An explosive composition of matter which is the product of the reaction resulting from the moistening without complete solution of a dry mixture of a nitrate selected from the group consisting of the nitrates of lead and calcium, with a 30 hypophosphate selected from the group consisting of the hypophosphites of potassium, sodium, calcium, strontium, ammonia, barium, and manganese.

2. An ammunition priming mixture containing 35 an explosive composition of matter which is the product of the reaction resulting from the moistening without complete solution of a dry mixture of a nitrate selected from the group consisting of the nitrates of lead and calcium, with a hypophosphate selected from the group consisting of the hypophosphites of potassium, sodium, calcium, strontium, ammonia, barium, and manganese. 40

3. The explosive composition of matter calcium 45 nitro calcium hypophosphate.

4. An explosive composition of matter which is the product of the reaction resulting from the moistening with a quantity of water insufficient to effect complete solution of a dry mixture of 50 lead nitrate and calcium hypophosphate.

5. An ammunition priming mixture containing an explosive composition of matter which is the reaction product resulting from the moistening with a quantity of water insufficient to effect 55 complete solution of a dry mixture of lead nitrate and calcium hypophosphate.

WILLI BRUN.
